UNITED STATES PATENT OFFICE.

VAN SCHAICK SHARP, OF WEEDSPORT, NEW YORK, ASSIGNOR OF ONE-HALF TO WALLACE W. HOLCOMB, OF SAME PLACE.

MACHINE FOR CROSS-TURNING SHEET METAL.

SPECIFICATION forming part of Letters Patent No. 317,585, dated May 12, 1885.

Application filed November 11, 1884. (No model.)

To all whom it may concern:

Be it known that I, VAN SCHAICK SHARP, a resident of Weedsport, in the county of Cayuga and State of New York, have invented certain new and useful Improvements in Machines for Cross-Turning Sheet Metal; and I do hereby declare that the following is a full, clear, and exact description of the invention, that will enable others skilled in the art to 10 which it appertains to make and use the same, reference being had to the accompanying drawings, and to the letters of reference marked thereon, which form a part of this specification.

15 Similar letters refer to similar parts in the several figures therein.

My invention relates to improvements in machines for cross-turning tin or other sheet metal.

20 The objects of my invention are, first, to provide a machine that will turn two edges at the same time; second, to provide a machine that may be operated from either side; third, to provide a clamping device for two edges of 25 the sheet metal that may be operated by a single treadle; fourth, to provide a machine for cross-turning two edges of sheet metal at the same time with an adjusting device, by which the machine may be readily adjusted to 30 sheets of tin of different lengths.

Figure 1 of the drawings is a side elevation of my improved device. Fig. 2 is a top plan view of same. Fig. 3 is a vertical section taken at broken line *x y* in Fig. 2, showing a 35 metal sheet in position to be clamped and bent. Fig. 4 is same, showing the sheet clamped and bent. Fig. 5 is an edge elevation of metal sheets with their bent edges hooked together. Fig. 6 is same with bent edges forced closely 40 together.

45 A represents a frame or bench supported by legs *A'*, and provided with horizontally-adjustable plates *B* and *B'*, one on each end. Superimposed upon these plates are other vertically-adjustable plates, *C* and *C'*. The latter plates are supported and held in position by the downwardly-projecting lugs *a a'*, which are connected at their lower ends by the links *m m'* with the two arms *l l'*. The arms at their 50 point of junction are connected with a treadle, *t*, by which they are operated. The springs

n, attached at their lower ends to the projecting arms and at their upper ends to the frame, serve to elevate the arms, links, and plates *C C'*, when the treadle is released, to the position shown in Figs. 1 and 3. A sheet of tin or any desired metal is then introduced from one end between the upper and lower plates and brought firmly against stop *b*, as shown in Fig. 3. The treadle is then operated, as before explained, to draw the plates *C C'* down to the position shown in Fig. 4, which tightly 60 clamps the sheet metal between the two sets of plates.

One of the upper plates, *C*, is provided with 65 a leaf, *D*, hinged thereto and held in line therewith by the spring *S*, fastened one end to the plate and the other end to the leaf.

When the plate *C* is drawn down to plate *B*, as before explained, the leaf *D* is adapted to 70 swing upon its hinges around to the position shown in Fig. 4, bending the sheet metal around the beveled edge of the plate *B*, as shown in said figure. On the other side of the frame the lower plate, *B'*, is provided 75 with the hinged leaf *D'*, adapted to swing and bend the sheet metal around the beveled edge of plate *C'*, as shown in Fig. 4.

To operate the hinged leaves, I provide an 80 axle, *J*, extending across the frame and having at each end a disk, *G*, adapted to support at different angles the operating-lever *L*, also one end of the links *H H'*, the other ends of the links being connected with the toothed segment-wheels *d d'*. The segments of the latter 85 are adapted to engage with the toothed segments *e e'*, provided with dogs or trips *h h'*, adapted to engage with the pins *g g'*, as shown in Figs. 1 and 2. It is evident, therefore, that a partial revolution of disk *G* will force the 90 leaves *D D'* from the plane of the tables to the position shown in Fig. 4. The upper plates are drawn down upon the sheet metal before the leaves *D D'* are operated, which brings the pin *g* down in front of trip *h* to be engaged 95 thereby. After the sheet metal is bent, as shown, the disks and segments are returned to their former position, (shown in Fig. 1,) and the treadle is released, whereupon the springs *n* throw the upper plates upward to the position 100 shown in Fig. 1. Plate *C'* is provided with a pin, *k*, which rides in the curved slot *j* of the

attachment *j'*, which is fixed to the frame *A*. The plate *C'* travels to the right as viewed in Fig. 1, as well as upward, being aided thereto by the spring *g'*, thus receding from its position within the bent edge of the sheet metal shown in Fig. 4 without effort to straighten the bent portion. The plates *B* and *B'* are connected by rods *O*, screw-threaded to the right at one end and to the left at the other, and provided with operating-handles *O'*, for revolving said rods in lugs *P*, projecting from *B* *B'*, and threaded to correspond with the threaded ends of said rods, the object being to provide means for adjusting the distance apart of the forming-edges of plates *B* and *C'* to the length of the sheet of metal to be operated upon, which is accomplished by revolving said rods to the right or left, as desired. The four lugs *a* are all secured to the upper plates, and pass down through guiding-slots in the lower plates. The stop *b* is spring-controlled, and recedes when the leaf *D'* is bent over to position shown in Fig. 4, which brings the stop in contact with plate *C'* and forces it back through plate *D'* 25 against its controlling-spring.

What I claim as new, and desire to secure by Letters Patent, is—

1. In a machine for cross-turning metal, the combination of plates *B* *B'*, nuts *P* *P*, rod *O*, 30 and stop *b*, whereby plates of varying length may be held, substantially as described.

2. In a machine for cross-turning metal, the two vertically-adjustable plates *C* *C'*, one having an undercut bevel and the other provided with a hinged leaf, *D*, in combination with a 35 bed having an undercut bevel at one end and at the other end a hinged leaf, *D'*, with a spring-stop, *b*, whereby the plates which are to be operated upon may be stopped, clamped, and turned, as described. 40

3. In a machine for cross-turning plates, the combination of the axle *J*, disks *G* *G*, lever *L*, links *H* *H'*, toothed segment-wheels *d* *d'* *e* *e'*, the trips *h* *h*, the pins *g* *g'*, and the spring *S*, whereby the hinged leaves may be operated, as described. 45

4. The combination, in a machine for cross-turning plates of metal, with a hinged leaf, *D'*, of a stop, *b*, held yieldingly by a spring, whereby it may operate, as described. 50

5. The combination, with the lugs *a* *a*, of the links *m* *m'*, arms *l* *l'*, springs *n* *n*, and treadle *t*, whereby plates *C* *C'* may be operated, as set forth.

In testimony whereof I have hereunto set my hand this 22d day of October, 1884. 55

VAN SCHAICK SHARP.
